UNITED STATES PATENT OFFICE.

WILLIAM H. BOUTELLE, OF STURBRIDGE, MASSACHUSETTS, ASSIGNOR TO AMERICAN OPTICAL COMPANY, OF SOUTHERIDGE, MASSACHUSETTS, A VOLUNTARY ASSOCIATION OF MASSACHUSETTS.

OPHTHALMIC MOUNTING.

Application filed October 29, 1924. Serial No. 746,549.

To all whom it may concern:

Be it known that I, WILLIAM H. BOUTELLE, a citizen of the United States, residing at Sturbridge, in the county of Worcester and 5 State of Massachusetts, have invented certain new and useful Improvements in Ophthalmic Mountings, of which the following is a specification.

This invention relates to improvements 10 in ophthalmic mountings and has particular reference to an improved composite mounting, that is, one comprising both metallic and nonmetallic parts, and to the provision of an improved method of producing the 15 same.

An important object of the invention is to provide an improved ophthalmic mounting wherein a metallic member is provided with a nonmetallic covering.

Another object is to provide such a covering which will be securely held in place by an interlocking member without the use of extraneous metal fastening means.

Another object is to provide an improved 25 method of producing such a mounting whereby the same may be practiced commercially in a practical manner.

With these and other objects in view, the 30 invention resides in novel features of construction, combination and arrangement of parts hereinafter set forth, illustrated in the accompanying drawings and particularly pointed out in the appended claims.

In the accompanying drawings forming a 35 part of this specification and wherein similar reference characters are used to designate corresponding parts throughout the several views:

Figure 1 is a front elevation of a complete 40 spectacle, having endpieces embodying the invention.

Figure 2 is a detail perspective view of the endpiece and its connecting parts.

Figure 3 is a vertical sectional view on the 45 line 3-3 of Figure 2.

Figure 4 is a vertical sectional view on the line 4-4 of Figure 2.

Figure 5 is a detail perspective view of one of the endpiece members.

Figure 6 is a top plan view of the metal 50 endpiece without its nonmetallic cover.

Figure 7 is a sectional view showing the application of the invention to the construction of a temple.

The spectacle illustrated in Figure 1 comprises the usual pair of lens receiving rims 10 connected by a bridge member 11 and provided at their opposite sides with endpieces generally designated by the reference character 12 to which are secured a pair of temples 13 of any ordinary or desired construction. As best shown in Figure 2, the lens receiving rims are formed by the combination of an inner metallic rim 14 and an outer nonmetallic rim 15, both of which are fastened together as by interlocking the ends 16 of the outer member over the inner rim 14. The outer rim 15 may be formed of any suitable nonmetallic material such as zylonite or other cellulose composition material and the covering of the temple 13 is also formed of a similar material.

The lens rims 10 are preferably split and the endpieces 12 are secured to the meeting ends of the rims as is usual. The outer portion of the endpieces is rearwardly disposed as illustrated at 17 in Figure 6 and the opposite faces of the endpieces are recessed so as to form a temple receiving groove 18 in which is positioned a pivoting post 19 of the usual type. The forward extremity 20 of the temple 13 is provided with an aperture 21 by which it is pivotally mounted upon the post 19, and the parts are securely held in place by a clamping screw 22 disposed in the endpiece members.

In order that the endpieces may harmonize with the lens rims 10 in appearance, I provide a pair of nonmetallic cup shaped members 23 formed to completely cover the endpiece members 12.

In order to facilitate fastening of the covering shells 23 to the endpiece members 12, I provide said endpiece members with a notch or recess 24 into which I introduce a nonmetallic plug member 25 which is, at its outer surface 26, flush with the edge of the endpiece member. In this way I can cement the inner surface of the shell 23 to the outer surface of the plug 25 since both members are made of the same kind of material that will become firmly united. In view of the fact that the notch or recess 24 is hand cut there will be no possibility of the plug member becoming accidentally displaced.

In Figure 7, I have illustrated the application of my improved structure to the construction of a temple wherein the extremity

20 of the temple is suitably notched or recessed as at 27 for the reception of a nonmetallic insert 28. The covering 13 of the temple is so formed that it may be extended 5 over the edge of the extremity 20 so as to overlie the insert 28 to which the nonmetallic covering 13 is secured as by cementing.

In use, the endpiece covering 23 will not interfere in any way with the separation of 10 the endpiece members 12, either for the insertion of lenses in the lens rim 10 or for the changing of the temple. Furthermore, it will be apparent that there is no possibility for said nonmetallic endpiece covering becoming loose, so that the metal endpieces 5 will be entirely concealed and their coverings will harmonize with the outer rim member 15.

From the foregoing it will be apparent 20 that I have produced an improved ophthalmic mounting, comprising metallic and nonmetallic parts secured together in a simple but reliable manner. Obviously, changes 25 may be resorted to in the minor details of construction and arrangement of parts, and the right is herein reserved to make such changes falling within the scope of the appended claims without departing from the spirit of my invention.

30 Having thus described my invention, what is claimed is:

1. An ophthalmic mounting comprising a metallic member provided in one of its surfaces with a recess, a nonmetallic plug secured in the recess, and a nonmetallic covering on a surface of the metallic member and secured to the plug.

2. An ophthalmic mounting comprising a metallic member provided in one of its surfaces with an undercut recess, a nonmetallic plug secured in the recess, and a nonmetallic covering secured to the outer surface of the plug and extending over the surface of the metallic member.

3. An ophthalmic mounting comprising a split lens receiving rim, endpieces carried by the meeting ends of the rim, each of said endpieces being notched, nonmetallic plugs

disposed in the notches, and a nonmetallic shell covering the endpieces and secured to 50 the plugs.

4. An ophthalmic mounting comprising a split lens receiving rim, endpieces carried by the meeting ends of the rim, said endpieces being provided with undercut recesses, nonmetallic inserts secured in the recess, and a nonmetallic shell covering the endpieces and fastened to the outer surface of the inserts.

5. An endpiece comprising a metallic 60 body portion having a recess in one of its surfaces, a nonmetallic insert disposed in the recess, and a nonmetallic covering on the body portion, said covering being cemented to the outer surface of the insert.

6. The method of producing a composite ophthalmic mounting consisting in forming a metal body member of the desired shape, providing a recess in one edge of the body member, inserting a nonmetallic member within the recess with its outer surface flush with the edge of the body member, forming a covering of nonmetallic material for the recessed edge of the body member, and securing said covering to the inserted nonmetallic member.

7. The method of producing a composite ophthalmic mounting consisting in forming a metal body member of the desired shape, providing an undercut groove in one edge 80 thereof, inserting a nonmetallic filler in the groove with its outer surface flush with the edge of the body member, forming a covering of nonmetallic material for the grooved edge of the body member, and cementing said covering to the outer surface of the nonmetallic filler.

8. The method of producing a composite ophthalmic mounting consisting in forming a metal body member of the desired shape, providing an undercut groove in one edge thereof, inserting a nonmetallic filler in the groove, forming a thin nonmetallic shell as a covering for the metal body member, and securing said shell to the nonmetallic filler.

WILLIAM H. BOUTELLE.
